UNITED STATES PATENT OFFICE.

OSCAR W. RICHARDSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DEVICE TO PREVENT VIBRATION OF BOBBINS.

Application filed April 1, 1924. Serial No. 703,545.

To all whom it may concern:

Be it known that I, OSCAR W. RICHARDSON, a citizen of the United States, residing at Worcester, in the county of Worcester and State of Massachusetts, have invented 5 new and useful Devices to Prevent Vibration of Bobbins, of which the following is a specification.

This invention relates to improvements 10 in weft replenishing mechanisms for looms and more particularly to devices for preventing the rotation of bobbins on their axes as they await transfer.

In the usual type of multi-color weft 15 replenishing mechanisms the bobbins are arranged loosely in vertical stacks and are discharged one by one to move to transfer position. It has been found that where the yarn is fine so that transfers are relatively infrequent the filling ends which extend to the 20 thread holder become entangled due to the rotation of the bobbins and breakage of the thread is likely to result at the time of transfer.

25 In my co-pending application, Serial No. 602,625 I have shown a weft replenishing mechanism having a plurality of compartments, each of which is formed with one fixed wall and one movable wall, the movable walls of the compartments being formed of thin spring stock riveted at their lower ends to the frame of the replenishing mechanism. These movable walls are under control of the replenishing mechanism 30 and are moved laterally with respect to the axes of the bobbins and engage the heads of the latter so that they are held against the fixed walls of the compartment and thus restrained against rotation or vibration.

35 40 Because of the fact that the walls of the compartment disclosed in my aforesaid application are formed of resilient material the bobbins are permitted a certain rotation which is more noticeable on the outer compartments of the mechanism. Also, the spring walls are likely to become deformed and protrude into the path of and interfere with the falling of the bobbins in the replenishing mechanism. It is one object of 45 my invention to afford more reliable means for preventing the rotation of the bobbins by providing each bobbin compartment with a weft replenishing mechanism controlled by a rigid wall pivoted at one end and spring 50 pressed against the bobbins to hold the lat-

ter against the fixed wall of the compartment. Such a construction provides for exerting greater and more uniform pressure on all of the bobbins in the compartment during normal running operation of the 60 loom and also permits immediate release of all bobbins at the time of indication of substantial weft exhaustion.

Another object of my invention is to provide mechanism which will in effect divide 65 each of the vertical bobbin compartments into a series of sub-compartments, one for each bobbin, whereby each bobbin may be more easily controlled and restrained.

A still further object of my invention is 70 to provide each bobbin compartment with a pivotal wall which is held yieldingly in bobbin restraining position by means independent of the other pivotal walls so that the number of bobbins in one compartment 75 will not affect the pressure of the walls in the neighboring compartments.

With these and other objects in view which will appear as the description proceeds, my invention resides in the combination and arrangement of parts hereinafter described and set forth in the claims. 80

In the accompanying drawing wherein I have shown two forms of my invention.

Fig. 1 is a side elevation of a two color 85 weft replenishing mechanism having my invention applied thereto and shown as viewed from the central portion of the loom,

Fig. 2 is a vertical section taken on line 90 2-2 of Fig. 1,

Fig. 3 is a horizontal section taken on line 3-3 of Fig. 1,

Fig. 4 is a perspective view of the upper portion of the compartments forming part 95 of the replenishing mechanism, and

Fig. 5 shows a portion of a modified form of movable wall.

Referring to Figs. 1 to 4 it will be seen that I have provided a weft replenishing 100 mechanism having a frame 10 on which are mounted slides 11 and 12 which are adapted for vertical motion in upper and lower guides 13 and 14 respectively. The lower ends of the slides are slotted as at 15 105 and 16, respectively, to cooperate with cradles 17 and 18, respectively, which control the discharge of the bobbins. Slide 11 is provided with upper and lower lugs 19 and 20, respectively, and slide 12 is similarly 110

formed with lugs 21 and 22, respectively. Mounted for longitudinal and angular motion with respect to the slides 11 and 12 is a rod 23 guided in bearings 24 and having secured thereto fingers 25, one of which is shown in Fig. 2. These fingers are positioned for engagement one by one, with the lugs on the vertical slides 11 and 12 and the rod 23 is moved longitudinally under control of the box motion to bring the proper finger in operative relationship with the slide corresponding to the active shuttle. The frame 10 is provided with fixed walls 26 and 27, respectively, which form the outer boundaries of compartments 28 and 29, respectively. The mechanism thus far described is of the usual construction and for a more complete showing and description thereof reference may be had to Patent No. 1,030,748.

My invention relates more particularly to the construction and mounting of the movable walls which form the inner boundaries of the compartments 28 and 29. Referring to Fig. 1 it will be seen that I have provided walls 40 and 41 which are pivoted at their lower ends to stationary parts of the mechanism, as at 42 and 43, respectively. These walls are substantially the same width as the fixed walls 26 and 27 and extend upwardly from their pivots to the upper portion of the replenishing mechanism as indicated in Fig. 1. As shown in Fig. 4, the surfaces of the movable walls adjacent their respective compartments are formed with corrugations 44 and 45, respectively, which are shallow at the lower ends of the walls and are made deeper toward the top, the depth of the corrugations being approximately proportional to their distance from the pivot of the wall.

Secured to the walls adjacent the upper portions thereof are cam plates 46 and 47, respectively, which are rigidly secured to the walls and extend from the latter through an opening 48 formed in the frame of the replenishing mechanism to the inner side of said mechanism. Springs 49 and 50, are connected to the cam plates 46 and 47, respectively, and serve to hold the walls against the bobbins in the associated compartments. As shown in Fig. 3 each cam plate is formed with a portion 51 so located as to engage the adjacent wall of the opening 48 when the corresponding compartment is empty, in this way forming a stop for the wall.

In order to provide for slight irregularities in the bobbins a modified form of wall may be employed such as shown in Fig. 5, where I have indicated the corrugated surface of the wall as being covered with a yielding surface 60 such as rubber, felt, leather or other flexible compressible material.

In the normal operation of the loom the vertical slides are in lower position as indicated by slide 11 in Fig. 1 and the movable walls are held against the corresponding stack of bobbins, each bobbin being received by one of the sub-compartments formed by the corrugations so as to be held against rotation and also against vertical motion. At indication of substantial weft exhaustion the slide corresponding to the indicating shuttle will be raised to the position indicated by slide 12 in Fig. 1 as set forth in the aforesaid Patent No. 1,030,748. When the slide is raised, the upper portion thereof will engage the corresponding cam and move the wall attached thereto away from the bobbins to permit the latter to fall freely to meet the requirements of the replenishing mechanism. The raised slide will remain in upper position until the indicating shuttle returns to the replenishing side of the loom, at which time the slide will be lowered to move out of contact with the cam and thus release the pivoted wall so that the same can move into contact with the associated stack of bobbins.

From the foregoing it will be seen that I have provided each bobbin compartment with a rigid pivoted wall normally held yieldingly against the bobbins of the corresponding compartment to prevent rotation thereof and controlled by the replenishing mechanism to release the bobbins at the proper time to permit them to fall freely to the next position before again being engaged by the wall. Also, the movable walls are provided with depressions which define a sub-compartment for each of the bobbins so that the latter are engaged by a larger surface than is the case where the wall is formed with a planate face. Furthermore, the pivoted walls are held in bobbin restraining position by independent means so that the bobbins of any compartment are not interfered with by the bobbins of any other compartment. While I have shown the adjacent walls of each pair of compartments as pivoted, yet I do not wish to be limited to this construction and it is to be understood that the movable walls may be formed either as shown in Fig. 1 or in Fig. 5.

Having thus described my invention, it will be apparent that changes and modifications may be made therein by those skilled in the art without departing from the spirit and scope of the invention and I do not wish to be limited to the details herein disclosed, but what I claim is:

1. In a weft replenishing mechanism for looms, a compartment to hold reserve bobbins as they await movement toward transfer position, a pivotally mounted wall forming one side of the compartment and extending adjacent the reserve bobbins, and means under control of the replenishing

mechanism to move said wall about the pivot therefor to vary the width of the compartment.

2. In a weft replenishing mechanism for looms, a compartment to hold reserve bobbins as they await movement toward transfer position, a pivotally mounted wall forming one side of said compartment and extending adjacent the reserve bobbins, and means to move said wall about the pivot therefor into and out of contact with the bobbins.

3. In a weft replenishing mechanism for looms, a compartment to hold reserve bobbins as they await movement toward transfer position, a pivotal member defining one side of the compartment and extending adjacent the reserve bobbins, and means under control of the weft replenishing mechanism to move said member into engagement with the bobbins in the compartment.

4. In a weft replenishing mechanism for looms, a bobbin compartment to hold reserve bobbins as they await movement toward transfer position, a fixed wall for the compartment, a rigid pivoted wall movable about the pivot thereof in a vertical plane and normally held toward the fixed wall and extending adjacent the reserve bobbins, and means under control of the replenishing mechanism to move said pivoted wall away from the fixed wall.

5. In a weft replenishing mechanism for looms, a bobbin compartment having a fixed wall, a movable wall pivoted at the lower end thereof to the replenishing mechanism and having the upper end thereof yieldingly held toward the fixed wall, and connections from the replenishing mechanism to move said pivoted wall away from the fixed wall.

6. In a weft replenishing mechanism for looms, a bobbin compartment, a movable wall for the compartment normally held in contact with the bobbins and having depressions formed therein to receive portions of the bobbins, and replenishing mechanism controlled means to move said wall out of contact with the bobbins.

7. In a weft replenishing mechanism for looms, a bobbin compartment, a wall for said compartment pivoted at the lower end thereof, and having formed therein a series of depressions, each depression adapted to receive portions of a bobbin, and replenishing mechanism actuated means for controlling the position of said wall.

8. In a weft replenishing mechanism for looms, a bobbin compartment, a movable wall for said compartment pivoted at one end thereof to the replenishing mechanism and having formed therein depressions which vary in depth according to the distance of the depression from the pivot, said wall being normally held against the bobbins to restrain rotation thereof and said depressions receiving portions of the bobbins, and replenishing mechanism actuated means to move the wall to bobbin releasing position.

9. In a weft replenishing mechanism for looms comprising a frame, a bobbin compartment formed on one side of the frame, a movable wall for said compartment pivotally mounted on the frame and yieldingly held in contact with the bobbins of the compartment, a member on the side of the frame opposite the bobbin compartment movable under control of the indicating mechanism, and means extending through said frame from said movable wall into the path of the member and positioned for engagement with the frame to limit the movement of the movable wall.

10. In a weft replenishing mechanism for looms, a bobbin compartment having a fixed wall, a pivotally mounted rigid wall for the compartment normally held toward the fixed wall and having formed therein a series of depressions which divide the main compartment into a plurality of sub-compartments each of which is adapted to receive a bobbin, and means under control of the replenishing mechanism to move said pivoted wall away from the fixed wall so that the bobbins may fall successively through the various sub-compartments.

11. In a weft replenishing mechanism for looms, a bobbin compartment having a fixed wall, a pivotally mounted wall for the compartment normally held toward the fixed wall and having depressions formed therein to receive portions of the bobbins, the portion of the pivoted wall in which the depressions are formed being provided with a yielding compressible material, and means under control of the replenishing mechanism to move said pivoted wall with respect to the fixed wall.

In testimony whereof I have hereunto affixed my signature.

OSCAR W. RICHARDSON.
